METHOD AND APPARATUS FOR CONTROL-
LING MATERIAL AND FLUID TO ROTAT-
ABLE DRUM PULVERIZERSAdolf Hesse, Worcester, Mass., assignor to Riley
Stoker Corporation, Worcester, Mass., a corpo-
ration of Massachusetts

Application December 12, 1946, Serial No. 715,679

7 Claims. (Cl. 241—19)

1

This invention relates to a method and apparatus for pulverizing material, and more particularly to pulverizing systems having provision for controlling automatically the feed of the material to the pulverizing zone.

In pulverizing various materials it is a common practice to employ an air-swept ball mill, such a mill comprising a rotatable drum or shell having loose grinding balls therein and means for producing a current of air through the drum to entrain and remove the finely pulverized particles of material in suspension. It is also a common practice to control the feed of the coarse material to the drum in such a manner as to maintain a substantially constant level of the material within the drum. I have discovered, however, that when grinding certain materials, such as coal, having varying moisture contents, there are disadvantages in maintaining a constant level within the drum. In particular, I have found that such a practice imposes serious limitations upon the capacity of the mill, for as the moisture content increases, the material tends to pack and adhere to the surface of the drum in a solid mass, thereby preventing the balls from cascading in the manner required for efficient pulverization. Attempts to overcome this difficulty by heating the air supply have been only partially successful.

It is accordingly one object of the invention to provide a method and apparatus whereby materials with varying moisture contents may be pulverized satisfactorily.

It is a further object of the invention to provide a method and apparatus for pulverizing material, such that the effect of variations in the moisture content of the material will be minimized so far as limiting the pulverizing capacity is concerned.

It is a further object of the invention to provide a ball mill and associated apparatus capable of handling moisture-bearing material and so constructed and arranged that the capacity of the mill will not be seriously affected by variations in the moisture content of the material.

It is a further object of the invention to provide a new and highly advantageous method and apparatus for controlling the feed of moisture-bearing material to a ball mill, such as to avoid serious limitations on the mill capacity with increasing moisture content.

With these and other objects in view, as will be apparent to those skilled in the art, the invention resides in the combination of parts and the steps of the process set forth in the speci-

2

fication and covered by the claims appended hereto.

Referring to the drawings illustrating one embodiment of the invention, and in which like reference numerals indicate like parts,

Fig. 1 is a longitudinal sectional view of a pulverizer and associated control apparatus;

Fig. 2 is an enlarged view showing a portion of Fig. 1 in detail; and

Fig. 3 is a fragmentary sectional detail of a portion of the control apparatus.

The embodiment illustrated comprises a horizontal rotatable drum or shell 10 forming a pulverizing zone and containing loose grinding bodies such as steel balls 11. Hollow trunnions 12 and 14 are provided on opposite ends of the drum, and these trunnions are rotatably supported in suitable bearings 15 and 16 respectively. Helical ribs 17 are provided on the interior surfaces of the trunnions to assist in retaining the balls within the drum.

An annular gear 18 is secured to the drum, and it will be understood that this gear is driven in known manner by a suitable pinion (not shown). Thus the drum will be rotated, and material within the drum will be pulverized by the impact of the cascading balls 11 upon the material. The fine material will be entrained and carried out of the drum by a current of a suitable gas, such as air, which travels through the drum.

The air, which is preferably heated in known manner, is delivered to the trunnion 14 through a stationary conduit 20, and it escapes through the trunnion 12 into a stationary conduit 21 leading to a fan 22. The conduit 20 is provided with an opening 24 through which relatively cold air from the surrounding atmosphere may be admitted under the control of a damper 25. Moisture-bearing material, such as

coal, is delivered to the drum 10 through a chute 27 leading to the trunnion 14 from a suitable feeder 28. This feeder is of a well-known type comprising a horizontal rotatable table 30 and a stationary blade 31 to deflect material from the table into the chute 27, the material being delivered to the table through a downspout 32. The table 30 is driven by an electric motor 34 which is connected to a suitable source 35 of electrical energy, the motor speed

being under the control of a rheostat 36.

It is desirable that the temperature of the air entering the drum 10 should vary with the moisture content of the entering material. With an increase in the moisture the air temperature should be increased in order that the necessary

heat may be available to dry the material and facilitates its pulverization. Accordingly there is provided a relay 38 of a well-known type having a crank arm 39 connected by a link 40 to the damper 25. This relay is supplied with electrical energy from a suitable source 42. The relay 38 is arranged to actuate the damper 25 in response to slight variations in the temperature of the air stream leaving the drum. For this purpose a temperature responsive bulb 43 is mounted within the duct 21 and connected to the relay by a tube 44 or other means for the transmission of control impulses to the relay. As an example of one suitable arrangement, the bulb 43 may contain a volatile liquid which produces an increasing fluid pressure upon an increase in temperature, the relay being constructed to respond to such changes in fluid pressure. With this arrangement, if the moisture content of the material entering the drum increases, an increased amount of heat will be absorbed from the air stream and utilized in evaporating the extra moisture, thereby lowering the temperature of the air in the outlet duct 21. The bulb 43 and the relay 38 will respond to this change in temperature and move the damper 25 toward its closed position, reducing the inflow of cold air through the opening 24, and increasing the temperature of the air stream entering the drum until the desired temperature adjacent the bulb 43 has been substantially restored. Similarly, a decrease in the moisture content of the entering material will result in a reverse movement of the damper 25. Consequently the temperature of the air stream in the duct 21 will be maintained substantially constant. To avoid excessive hunting, the relay 38 is preferably constructed with a time delay mechanism, in known manner.

I have discovered that superior operating results will be obtained if the level of the material within the drum 10 is varied in accordance with the moisture content of the entering material. By lowering this level upon an increase in the moisture content, it is feasible to operate the mill at a higher grinding rate than would otherwise be possible. Apparently, by decreasing the quantity of the material within the drum, in relation to the quantity of balls, the tendency of the material to pack into a solid mass is reduced. In order to bring about this variation in level, I preferably employ a control device which is responsive to the level of the material within the drum, and I connect the relay arm 39 to this device so that it will be raised or lowered as the damper 25 is closed or opened, the position of this damper being an indication of the moisture-content of the material supplied by the feeder. The control device is arranged to transmit a control impulse to a relay, which in turn actuates the rheostat 36 and thereby regulates the rate at which the material is fed to the drum.

In the particular embodiment illustrated, there is provided a generally horizontal pipe 46 which extends through the trunnion 12 and into the adjacent portion of the drum 10, the inner end of the pipe being bent downwardly. This pipe is pivotally supported or fulcrumed, intermediate its length on the outer wall of the duct 21, through which the pipe extends. As best shown in Fig. 2, the pipe 46 passes diametrically through a horizontal cylindrical member 47 and is held in place therein by a set-screw 48. This member 47 is mounted in a cylindrical socket 50 in

the duct wall, a portion 51 of this socket being removable to facilitate assembly of the parts. The outwardly extending portion of the pipe 46 is connected to the relay arm 39 by a flexible cable 53 which passes over an idler sheave 54, a weight 55 being provided to keep the cable taut.

Within the inner end of the pipe 46 there is provided an electric switch (Fig. 3) comprising a pair of stationary contacts 57 mounted on a disk 58 of insulating material. Beneath the disk 58 there is provided a diaphragm 59 of a suitable flexible material, such as rubber, having on its upper surface a contact member 60 adapted to bridge the contacts 57 upon upward movement of the diaphragm. The disk 58 and the diaphragm 59 are separated by a spacer ring 62, and the various parts are held in place by a threaded ring 63 directly beneath the diaphragm. Two insulated wires 64 extend upwardly from the respective contacts 57, through the pipe 46, and thence through a flexible tube 66 (Fig. 1) which connects the outer end of the pipe to a relay 67. This relay is of a well-known type having a crank arm 68 connected by a link 69 to the rheostat 36 to actuate the same, the relay being supplied with electrical energy from a suitable source 70. It will be understood that closure of the switch 57-60 will complete a low-voltage circuit through the wires 64, thereby transmitting a control impulse to the relay 67, which will respond by moving the crank arm 68 and adjusting the rheostat 36. The relay 67 is preferably constructed in known manner with a time-delay mechanism to avoid excessive hunting.

If desired, the wires 64, the contacts 57 and 60, the disk 58, the diaphragm 60, and the rings 62 and 63 may all be omitted, leaving the inner end of the pipe 46 entirely open. In that case, the relay 67 will be constructed to respond in known manner to variations in air pressure transmitted thereto through the pipe 46 and the flexible tube 66.

The operation of the invention will now be apparent from the above disclosure. The drum 10 will be rotated, causing the balls 11 to pulverize the material therein by their cascading action in known manner. Coarse material will be delivered to the drum by the feeder 28 under the control of the rheostat 36. The fan 22 will draw hot air through the duct 20, the drum 10, and the duct 21, this air entraining finely pulverized particles of material in the drum. Cold air will be drawn through the opening 24, under the control of the damper 25, thus reducing the temperature of the air entering the drum. If the moisture content of the material supplied to the drum increases, more heat will be absorbed from the air in evaporating this moisture, and the temperature within the outlet duct 21 will decrease slightly. The bulb 43 will immediately sense this decrease, causing the relay 38 to respond and swing the crank arm 39 to the right, partially closing the damper 25 and reducing the quantity of cold air admitted through the opening 24 to prevent any appreciable drop in the temperature within the duct 21. As the arm 39 moves to the right, the cable 53 will raise the outer end of the pipe 46 and lower the inner end thereof into the mass of material within the drum 10. As the diaphragm 59 comes into firm contact with the material, the switch 57-60 will be closed, sending an electrical impulse through the wires 64 to the relay 67, and the relay will adjust the rheostat 36 to reduce the feed of material

supplied by the feeder 28 to the drum 10 until the level therein has dropped sufficiently to open the switch 57-60 and reverse the relay. Similarly, if the moisture content of the material entering the drum decreases, less heat will be absorbed from the air, the bulb 43 will sense a slight rise in temperature, and the relay arm 39 will swing to the left. This will open the damper 25 to admit more cold air, and at the same time it will lower the outer end of the pipe 46 and raise the inner end thereof. The diaphragm 60 will be lifted out of contact with the mass of material within the drum, the switch 57-60 will open, and the relay 67 will adjust the rheostat 36 to increase the feeding rate of the feeder 28 until the level of material within the drum has been raised to bring the material into contact with the diaphragm 59 and close the switch 57-60, thereby reversing the relay.

If the diaphragm 59 and the associated parts 57, 58, 60, 62, 63, and 64 are omitted, and the relay 67 is constructed to respond to pneumatic pressure impulses rather than to electrical impulses, the general operation of the entire apparatus will not be affected. Lowering the inner end of the pipe 46 into the material will increase the air pressure within the pipe and the relay will respond by reducing the feeder speed until the material level has been correspondingly lowered. Raising the inner end of the pipe out of the material will decrease the air pressure within the pipe and the relay will respond by increasing the feeder speed until the material level has been correspondingly raised.

It will thus be seen that the level of the material within the drum will be automatically lowered when the moisture content of the entering material increases, and automatically raised when the moisture content decreases. This method of level control greatly decreases the tendency of the material to pack into a solid mass when the mill is operating at high capacity, and it makes it possible to increase the output of the mill very appreciably without danger of such packing. It also renders it unnecessary for the operator to be so careful as heretofore in avoiding the feeding of unduly wet material.

The inner portion of the pipe 46, whether or not the switch 57-60 is included, may be described as a level-sensing device, since it is arranged to provide control impulses, either pneumatic or electrical, for the relay 67 in response to variations in the spatial relationship between itself and the level of the material within the drum. It will be noted that the effect on the relay will be the same whether the sensing device is lowered or the material level is raised. In either case the relay will reduce the feeding rate. Similarly, either a raising of the sensing device or a lowering of the material level will cause the relay to increase the feeding rate. As a result the material level will remain close to the sensing device at all times, regardless of the position to which the latter may be moved in response to variations in the moisture content of the material.

Having thus described my invention, what I claim as new and desire to secure by Letters Patent is:

1. Pulverizing apparatus comprising a rotatable drum, loose grinding bodies within the drum, regulatable feeding means to supply moisture-bearing material to the drum to be pulverized therein, means producing a current of hot gas through the drum to entrain and remove fine particles of material in suspension, a controller

for the feeding means, a level-sensing device arranged to provide control impulses for the controller in response to variations in the spatial relationship between the said device and the level of the material within the drum, and means to raise or lower the level-sensing device as the temperature of the gas leaving the drum increases or decreases respectively.

2. Pulverizing apparatus comprising a rotatable drum, loose grinding bodies within the drum, regulatable feeding means to supply moisture-bearing material to the drum to be pulverized therein, means producing a current of hot gas through the drum to entrain and remove fine particles of material in suspension, a level-sensing device located within the drum, connections between the level-sensing device and the feeding means to increase or decrease the feeding rate as the distance between the said device and the level of the material within the drum increases or decreases respectively, and means to raise or lower the level-sensing device as the temperature of the gas leaving the drum increases or decreases respectively.

25 3. Pulverizing apparatus comprising a rotatable drum, loose grinding bodies within the drum, regulatable feeding means to supply moisture-bearing material to the drum to be pulverized therein, means producing a current of hot gas through the drum to entrain and remove fine particles of material in suspension, the heat in the gas serving to evaporate moisture from the material and the temperature of the gas being thereby reduced, a regulator arranged to vary the temperature of the gas entering the drum in accordance with the temperature of the gas leaving the drum, a level-sensing device located within the drum, connections between the level-sensing device and the feeding means to increase or decrease the feeding rate as the distance between the said device and the level of the material within the drum increases or decreases respectively, and means connecting the said regulator to the level-sensing device to raise or lower the said device as the temperature of the gas entering the drum is decreased or increased respectively.

40 4. Pulverizing apparatus comprising a rotatable drum, pulverizing means within the drum, regulatable feeding means to supply moisture-bearing material to the drum to be pulverized therein, a fan arranged to draw a current of hot air through the drum to entrain and remove fine particles of material in suspension, the heat in the air serving to evaporate moisture from the material and the temperature of the air being thereby reduced, means including a damper to admit relatively cool air for mixture with the hot air entering the drum, a regulator arranged to control the damper in accordance with the temperature of the air leaving the drum, a level-sensing device located within the drum, connections between the level-sensing device and the feeding means to increase or decrease the feeding rate as the distance between the said device and the level of the material within the drum increases or decreases respectively, and means connecting the said regulator to the level-sensing device to raise or lower the said device as the damper is opened or closed respectively.

45 5. Pulverizing apparatus comprising a rotatable drum, pulverizing means within the drum, regulatable feeding means to supply moisture-bearing material to the drum to be pulverized therein, an inlet duct to supply hot air to the drum, an air outlet duct connected to the drum,

a fan connected to the outlet duct to draw air through the drum to entrain and remove fine particles of material in suspension, the heat in the air serving to evaporate moisture from the material and the temperature of the air being thereby reduced, means including a damper to admit relatively cool air to the inlet duct for mixture with the hot air entering the drum, a regulator arranged to control the damper in accordance with the temperature of the air in the outlet duct, a level-sensing device located within the drum, connections between the level-sensing device and the feeding means to increase or decrease the feeding rate as the distance between the said device and the level of the material within the drum increases or decreases respectively, and means connecting the said regulator to the level-sensing device to raise or lower the said device as the damper is opened or closed respectively.

6. The method of operating a pulverizer of the type having a rotatable drum containing loose grinding bodies comprising the steps of supplying moisture-bearing material to the drum for pulverization by the grinding bodies, causing a current of hot gas to flow through the drum to entrain fine particles of the material and carry them in suspension out of the drum, the heat in the gas serving to evaporate moisture from the material and the temperature of the gas being thereby reduced as the gas travels through the drum, and controlling the rate of supply of the material in accordance with both the level of the material within the drum and the temperature of the gas leaving the drum as required to lower the said level upon a decrease in the temperature of the gas leaving the drum and vice versa.

7. The method of operating a pulverizer of the type having a rotatable drum containing loose grinding bodies comprising the steps of supplying moisture-bearing material to the drum for pulver-

ization by the grinding bodies, causing a current of hot gas to flow through the drum to entrain fine particles of the material and carry them in suspension out of the drum, the heat in the gas serving to evaporate moisture from the material and the temperature of the gas being thereby reduced as the gas travels through the drum, controlling the temperature of the gas entering the drum in accordance with the temperature of the gas leaving the drum, and controlling the rate of supply of the material in accordance with both the level of the material within the drum and the temperature of the gas leaving the drum as required to lower the said level upon a decrease in the temperature of the gas leaving the drum and vice versa.
